UNITED STATES PATENT OFFICE.

DANIEL M. SHEEDY, OF POUGHKEEPSIE, NEW YORK.

AUXILIARY AIR-INLET AND PRIMER FOR INTERNAL-COMBUSTION ENGINES.

1,111,620.

Specification of Letters Patent. Patented Sept. 22, 1914.

Application filed September 12, 1913. Serial No. 789,469.

To all whom it may concern:

Be it known that I, DANIEL M. SHEEDY, a citizen of the United States, residing at Poughkeepsie, in the county of Dutchess and State of New York, have invented certain new and useful Improvements in Auxiliary Air-Inlets and Primers for Internal-Combustion Engines; and I do declare the following to be a full, clear, and exact description of the invention, such as will enable others skilled in the art to which it appertains to make and use the same.

This invention relates to internal combustion engines the cylinders of which are supplied with gaseous fuel and air and more especially to an improved auxiliary air inlet device and primer for effecting a saving in fuel.

The object of the invention is to provide a combined auxiliary air inlet device and primer of this character which serves as a trap for the priming fluid and also as a heater for the incoming air.

Another object of the invention is to provide a simple and efficient device of this character for admitting auxiliary air to the intake pipe or manifold of a gasolene engine between the carburetor and the engine whereby the air and gaseous fluid are thoroughly mixed prior to the admission thereof into the engine to provide for the consumption of a minimum quantity of fluid in the working of the engine without the loss of the requisite driving energy thus enabling the different speeds to be obtained with the least possible amount of fuel supply.

With these and other objects in view, the invention consists of certain novel features of construction, and the combination and arrangement of parts as will be more fully described and claimed.

In the accompanying drawings: Figure 1 represents a side elevation of this improved device shown applied to the manifold of an internal combustion engine with parts of said manifold broken out and parts in section; Fig. 2 represents a plan view of the device with the manifold shown in horizontal section; Fig. 3 is a detail vertical section through the priming cup and the end of the pipe to which it is attached.

In the embodiment illustrated, an engine manifold 1 is shown to which this improved device is connected in any suitable manner the manifold being here shown provided with an internal threaded opening with

which a threaded end of the attachment is engaged.

This improved device comprises a hollow casting 2 having a threaded neck 3 for insertion in the threaded opening in the manifold, said neck being preferably provided with a collar 4 which abuts against the outer face of the manifold, a valve 5 is arranged in this casting and is provided with a stem 6 for opening and closing the valve. A coiled metal pipe 7 is connected at one end with the valve casing 2 in advance of the valve, said casing being here shown provided with a mouth 8 in which the end of the pipe is secured in any suitable manner thereby providing communication between the pipe and the valve casing. The coils of this pipe, any desired number of which may be employed, are arranged vertically as shown to provide a trap for the priming fluid for a purpose to be described. Two coils are here shown in the pipe but more may be formed if desired. The larger the number of coils the greater will be the heat effect on the air drawn in therethrough as these coils being metal become heated when the engine is in operation in a manner to be described. The free end 9 of the pipe 7 is disposed in upright position and the terminal thereof is exteriorly threaded as shown at 10, said threaded end being here shown enlarged and a shoulder 11 provided on its inner face at a point spaced from its extreme outer end.

A priming cup 12 having an opening 13 in the bottom thereof is provided with a tubular internally threaded shank 14 which is adapted to be adjustably connected with the exteriorly threaded end 9 of the pipe 7. A coiled spring 15 is disposed in the end 9 of the pipe 7 and in the shank 14 of the cup 12 and one end of said spring rests against the shoulder 11 of the pipe end and the other end of said spring extends into said shank. A ball valve 16 is disposed between the outer end of the spring 15 and the inner end of the shank 14 being designed to normally close the opening 13 in the priming cup, the spring 15 holding said ball valve normally in closed position. The tension of this spring 15 may be varied by adjusting the shank 14 of the cup 12 on the thread 10 on the pipe end 9, it being obvious that when said shank is moved inward the tension of the spring 15 will be increased and when it is moved outward it will be reduced. The shank 14 is

shown here provided with a wrench engaging face 17 for screwing the cup onto and off the pipe end.

In the use of this device when the threaded neck 3 has been engaged with the manifold 1, if the engine is already running, the valve 5 is opened to permit air to be drawn in through the cup 12 and the coils of the pipe 7 into the manifold which occurs on each suction stroke of the engine, the suction opening the valve 16 against the tension of the spring 15 and drawing in the desired quantity of air which is to be mixed with the gaseous fuel in the manifold. The heat from the engine will be imparted to the manifold by conduction and from the manifold through the casting or valve casing 2 to the pipe 7 and consequently when the air is drawn in through said pipe 7 it will be heated more or less before its entrance to the manifold, thereby greatly increasing its efficiency.

When difficulty is experienced in starting the motor such as frequently occurs in cold weather, it is desirable that a priming fluid be supplied with the gaseous fuel entering from the carburetor to enrich the charge drawn into the engine cylinder and a cup 12 here shown is especially designed for this purpose. The gasolene or other priming fluid is poured into the cup 12 and when the engine is cranked the suction thereof will open the valve 16 and draw the fluid into the pipe 7 through the coils thereof into the manifold and it will be found that this additional fluid will effectively prime the engine

for starting. The first suction stroke of the engine will draw in only a portion of the priming fluid as a part thereof will be held in the trap formed by the coils in the pipe and a second stroke of said engine piston will draw in additional fluid and thus insure the starting of the motor with little effort on the part of the operator.

While I have described my invention with more or less minuteness as regards details and as being embodied in certain precise forms, I do not desire to be limited thereto unduly any more than is pointed out in the claim. On the contrary, I contemplate all proper changes in form, construction and arrangement, the omission of immaterial elements and substitution of equivalents as circumstances may suggest or render expedient.

I claim as my invention:

An auxiliary air inlet and primer for internal combustion engines comprising a hollow valved casting having means for connection with an engine manifold, a coiled metal pipe connected with said casting in advance of the valve thereof, and a valved priming cup mounted on the free end of said coiled pipe, the coils of said pipe being disposed in vertical position.

In testimony whereof I have hereunto set my hand in the presence of two subscribing witnesses.

DANIEL M. SHEEDY.
